UNITED STATES PATENT OFFICE.

BOLESLAW V. CZARNECKI, OF SCHENECTADY, NEW YORK.

DESIGN FOR GLASS-TUMBLER HOLDER.

Application filed March 11, 1922. Serial No. 1,115. Term of patent 3½ years.

To all whom it may concern:

Be it known that I, BOLESLAW V. CZARNECKI, a citizen of the United States, residing at Schenectady, in the county of Schenectady and State of New York, have invented a new, original, and ornamental Design for Glass-Tumbler Holder, of which the following is a specification, reference being had to the accompanying drawing, forming part thereof.

Fig. 1 is a front elevational view, and
Fig. 2 is a side elevational view of the device.

I claim:

The ornamental design for glass tumbler holder.

BOLESLAW V. CZARNECKI.
